UNITED STATES PATENT OFFICE

JULIUS BROMBACHER, OF SANTA MONICA, CALIFORNIA

WATER HEATER

Application filed June 29, 1929. Serial No. 374,876.

My invention relates to heaters of the storage type and it has especial reference to a means for mounting the tanks of such heaters to facilitate their removal and replacement.

5 Water heating units of present day construction consist generally of a hot water storage reservoir suitably insulated or contained within and secured to an insulating jacket. Owing to the union between the tank and jacket, it is extremely difficult, time consuming and expensive to dissociate or 10 assemble the tank from the organized heater, and this cannot be done by anyone save a skilled workman.

15 The objects of the present invention therefore are to provide a mount for tanks of heating units by which the tanks may, after making the disconnections with gas and water lines, be readily removed without disturbing the insulation or causing any other annoyance. Another object of the invention is to provide a means in connection with the tank of a water heater whereby such tank may be readily locked in place within or to 20 the insulation or insulating jacket and unlocked so that the removal of the tank may be possible.

25 Another object of the invention is to provide a heating device of the storage type in which the tank is supported in such wise that its entire area is exposed to the heat from the burners.

These and other objects are accomplished by an arrangement expressed in preferable 30 form in the drawing which forms a part of this specification and in which.

Fig. 1 is an elevational sectional view showing my invention.

Fig. 2 is an enlarged elevational section 40 on line 2-2 Fig. 1.

Fig. 3 is an enlarged side view of the mutually engaging clips.

Fig. 4 is an enlarged side view of the mutually engaging means for preventing rotation of the tank, and

Fig. 5 is an enlarged front view of Fig. 4. In a general sense, the invention consists in mounting or supporting a storage tank within a shell, preferably an insulating jacket in such wise and manner that it may be quickly dissociated or removed from the jacket or insulating envelope by anyone without the exercise of any especial skill; it also consists of the novel relation of the water tank to the jacket by reason of which all the heat from the burners or other source is utilized in heating the water in the tank; and finally it consists of the specific means by which the ready association of the tank with and its dissociation from its complementary enveloping insulation may be effected.

In its specific aspect, the invention as shown in the drawing comprises a water heating unit of the type known in the art as storage heaters, in which the water is heated by any heating medium and stored until used, and such water heating unit consists principally of a storage tank and insulating jacket 2, and such other instrumentalities, not shown, as are generally complements of water heaters, and which forming no part of this invention, need no description.

As seen in Fig. 1, the insulating jacket 2 consists preferably of two spaced shells 2' and 2'', conjoined in suitable manner to form a single unit and the insulating unit envelopes the tank 1 at the sides and top thereof being spaced therefrom a distance sufficient to provide for a free circulation of the heat around the tank. The top of the insulating jacket 2 is provided with a hollow connection 3 for a pipe, not shown, to lead off the gases of combustion from the space between the tank and jacket. Centrally of the top, the insulating jacket 2 is provided with an opening 4 for the accommodation of a collar or sleeve 5, that is provided with a flange 6, arranged for engagement with the inner shell 2' of the insulating jacket. This collar or sleeve 5, is arranged to be fitted

over a fitting 7, that is threadedly connected with the top of the tank 1, and extends through the top of the jacket 2. The fitting 7 is provided with means 8 for connection to 5 a cold water supply, a pipe 9, for conveying the water to the bottom of the tank, and with an outlet 10 for leading off the hot water from the tank 1, through a pipe, not shown, and arranged to thread in said outlet 10. 10 By means of a set screw 11, the sleeve or collar 5 is arranged to be secured upon the fitting 7 so that the flange 6 thereof is in engagement with the horizontal portion of the inner shell 2' of the jacket 2. When the sleeve 15 or collar 5 is in the position, shown in Fig. 1, the tank 1 is rigidly locked against movement relatively to the top of the jacket 2, and it will be obvious that such relative movement of the tank 1 may be effected by releasing 20 the collar or sleeve 5 by unscrewing the set screw 11.

The tank 1 is supported within and free of the insulating shell by a series of equally spaced outwardly and downwardly bent 25 members 12 which are welded or otherwise secured to the tank 1 near the bottom thereof. These outwardly and downwardly bent members 12 co-operate with outwardly bent and upwardly extending members 13 which are 30 preferably riveted to the inner shell 2' of the insulating jacket 2, in supporting the tank 1 within the jacket. One of the outwardly and upwardly extending members, namely 14, is constructed to co-act with its 35 complementary member 12 in locking the tank 1 in position and preventing movement of same in a circular direction and a consequent accidental disengagement of the mutually engaging members 12, 13 and 14, by 40 reason of which the tank 1 would no longer be supported. For this purpose, the member 14 is provided in the upper edge thereof with a central recess 14' for the accommodation of one of the outwardly and downwardly 45 bent members 12, which after being seated in the recess 14' is restrained against circular movement with the tank 1 by the upstanding lateral projections 14'' resulting from the provision of the recess 14' in the member 14. 50 In Fig. 1, the members 12 on the tank 1 are shown in engagement with the members 13 and member 14 on the jacket, and the collar or sleeve 5 is fastened to the fitting 7, with the flange 6 thereof in engagement with 55 the top portion of the inner insulating shell 2'. In this position, the tank 1 is securely held within the jacket 2 against any movement. When for any reason it is desired or required to remove the tank 1 from the jacket 60 2, the required pipe disconnections being first made, the collar or sleeve 5 is unlocked from the fitting 7, by manipulation of the set screw 11, whereby it (the collar), drops upon the top of the tank 1 as shown in dotted lines, 65 Fig. 1. The tank 1 is then elevated to a

height sufficient to cause one of the members 12 thereon to disengage from the recessed member 14 on the jacket 2, and during this elevation of the tank 1, the fitting 7 is projected beyond the jacket 2. While thus elevated the tank is rotated to an extent sufficient to cause the members 12 on the same to be moved out of alignment with the members 13 and 14 on the jacket 2. Thereupon the tank 1 may be withdrawn from the jacket 2.

What I claim, is:

1. In a water heater, an insulating jacket, a tank having a fitting at the top thereof extending through the top of said jacket, mutually engaging means on said tank and jacket to support said tank free of said jacket and prevent movement thereof in a circular direction, and means arranged to be secured to said fitting to prevent longitudinal movement of said tank in one direction.

2. In a water heater, an insulating jacket, a tank having a fitting at the top thereof extending through the top of said jacket, mutually engaging means on said tank and jacket to support said tank free of said jacket and one of said means arranged to lock said tank against movement in a circular direction, and adjustable means arranged to be secured to said fitting to prevent longitudinal movement of the tank in one direction.

3. In a water heater, an insulating jacket, a tank provided with a fitting at the top thereof and extending through the top of said jacket, a plurality of members on and near the bottom of said tank, a plurality of members on and near the bottom of said jacket, and arranged for engagement by the members on said tank to support said tank free of the jacket, one of the members on said jacket having means for preventing the circular movement of said tank, and means arranged to be secured to said fitting and engaging said jacket to prevent movement of said tank longitudinally in one direction.

4. In a water heater, an insulated jacket, a tank, a fitting thereon, means on the tank and jacket arranged for mutual engagement to support the tank free of the jacket and prevent the circular movement of the tank while the supporting means are mutually engaged, and an adjustable collar arranged to be fastened on said fitting, and provided with a flange arranged to engage said jacket and thereby prevent the longitudinal movement of said tank in one direction.

5. In a water heater, an insulating jacket, a tank having a fitting thereon extending through the top of said jacket, a plurality of outwardly and upwardly extending members secured to said jacket, one of said members having a recess, a plurality of downwardly and outwardly extending members secured to said tank and arranged for mutual engagement with the members on said

jacket, one of the members on said tank being arranged for engagement with the recessed member on said jacket to lock same against movement in a circular direction, a flanged sleeve adjustable on said fitting to cause the flange thereof to engage the top of the jacket and means to lock said sleeve in adjusted position on said fitting thereby to prevent movement of the tank longitudinally in one direction.

In testimony whereof I have set my hand.
JULIUS BROMBACHER.
